SCAFFOLD

Henry J. Kruse, St. Charles, Mo.

Application January 5, 1939, Serial No. 249,531

1 Claim. (Cl. 304—27)

This invention relates to scaffold construction and particularly to scaffolds designed for use in washing or repairing windows.

An important object of the invention is to provide a scaffold of this character which may be folded into a small and compact article to facilitate the storing and shipping of the scaffold.

Another object of the invention is to provide a scaffold which will be exceptionally light in construction so that the scaffold may be easily handled, due consideration being given to the strength and durability of the scaffold.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is an enlarged side elevational view of a scaffold constructed in accordance with the invention, as positioned adjacent to a window.

Figure 2 is a plan view thereof.

Figure 3 is a front elevational view of the scaffold.

Figure 4 is a view illustrating the scaffold in its folded position.

Referring to the drawings in detail, the scaffold comprises spaced vertical bars 5 formed with offset portions at a point adjacent to the upper ends thereof, the offset portions providing shoulders 6 adapted to fit over the window sill of a window. These bars 5 rise from one end of the bars 7, on which the flooring 8 is secured, the connection between the bars 5 and 7, being made by means of the rod 9 that passes through openings formed in the bars 5 and 7, the bars being secured against displacement, by means of the nuts 10.

At the opposite end of the bars 7, are spaced vertical bars 11 which are secured to the bars 7 at opposite sides of the scaffold, by means of the rod 12 which is shown as extending through registering openings in the bars 7 and 11. Nuts 13 are secured at the ends of the rods 12, and secure the bars 11, the nuts being positioned in such a way as to allow pivotal movement of the bars 11 with respect to the bars 7. The upper ends of the bars 5 and 11 at one side of the scaffold, are connected by means of the bar 14, which has pivotal connection with the bars 11 so that piv-

otal movement of the scaffold frame will be permitted. The bars 5 and 11 at the opposite side of the scaffold frame are pivotally connected with the bar 15. Pivotally connected with the bars 7 at opposite sides of the frame, are bars 15, which are slightly curved, as clearly shown by Figure 1 of the drawings. The connection between the bars 15 and bars 7, is made through the bolts 16. These bars 15 are provided with elongated openings 17 that accommodate the ends of the rod 18 that extends through the bars 5, the rod 18 being held in position by means of nuts 19. Thus it will be seen that when these nuts 19 are tightened, the bars 15 will be securely held against the bars 5, and against movement with respect to the bars 5. The upper supporting bars of the scaffold are arranged at opposite sides thereof, each bar including slidably connected sections 20 and 21, the section 20 having extensions 22 that are bent over the section 21, while the section 21 is formed with extensions that are bent over the section 20, providing this slidable connection. The bars 20 and 21 are provided with openings in which the bolts 23 are positioned, the bolts being provided with winged nuts 24, whereby the sections 20 and 21 may be drawn into close engagement with each other after the proper adjustment has been made. The bars 15 have pivotal connection with the bars 21, through the bolts 25. These supporting arms have pivotal connection with the diagonally disposed brace bars 26, at 27, the opposite ends of the bars 26 being connected to the bars 5 near the lower ends thereof, as at 28.

As shown, the outer ends of the sections 20, 35 extend downwardly, where they are supplied with elastic cushioning members 29, which are designed to hook over the window sill, and cooperate with the shoulders 6 in gripping the window sill.

In order that the scaffold may provide a guard against a person leaning rearwardly, falling from the scaffold, the upper ends of the bars 11, extend appreciable distances above the bars 14, where they are connected by means of the rod 30. This rod 30 also provides a handle whereby the person using the scaffold may steady himself, while at work.

A rod 31 connects the bars 11 near the lower end thereof, and acts to hold the bars 11 in predetermined spaced relation with respect to each other at all times.

Thus it will be seen that due to the construction shown and described, I have provided a scaffold which may be readily and easily un-

folded or extended to a position as shown by Figure 1 of the drawings, whereupon the scaffold may be positioned over a window sill as shown, thereby providing a scaffold which may be used 5 by a window washer or person repairing the window, to the end that the work may be accomplished with facility.

What is claimed is:

10 A scaffold comprising a rectangular frame embodying parallel upper and lower side bars and vertical front and rear bars, the inner ends of the upper side bars extending downwardly and adapted to hook over a window sill, diagonally disposed adjustable bars pivotally connected to

the upper and lower side bars and having elongated openings formed therein, bolts extending from the vertical front bars and operating in the elongated openings, nuts on the bolts for securing the diagonally disposed bars in various positions of adjustment, the lower ends of the diagonally disposed bars being curved outwardly, diagonally disposed bars pivotally connected with the vertical front bars and upper side bars, the latter diagonally disposed bars crossing the first 10 mentioned diagonally disposed bars, and a flooring on the scaffold. 5

HENRY J. KRUSE.
